HERMETICALLY SEALED SWITCH

In my U.S. Pat. No. 3,431,378, granted Mar. 4, 1969, and assigned to the assignee of the present invention, there is disclosed a similar hermetically sealed electrical switch. This switch is positioned within a sealed container and is actuated by a physical movement against its blade to cause the blade to change, by snap action, from engaging one contact to engaging another contact. For transmitting the actuating movement from outside of the container to the switch, the container is formed with a cylindrical tube that is relatively easily radially distortable. Thus the actuating movement is transmitted to the switch by applying a radial force against the sidewall of the tube that is in alignment with the switch blade and the tube bends along its axis to transmit the motion into the container.

While such an hermetically sealed switch has been found to be exceedingly satisfactory, the type of actuator disclosed in my above-noted patent has been found to not be completely acceptable. In such a switch it is necessary that the mechanical operating points be maintained substantially constant during use and one difficulty with the heretofore utilized actuator has been caused by the actuator being capable of being physically deformed when subjected to overtravel movement. Moreover, as the actuator is required to flex to transmit the movement, attempts to increase the actuator's rigidity have not been successful as it increased the force required to flex the actuator in order to actuate the switch.

It is accordingly an object of the present invention to provide an hermetically sealed electric switch in which the movement for actuating the switch is transmitted by distortion of a tube, but yet in which the mechanical operating characteristics of the switch are maintained substantially constant even over a wide range of operating conditions.

Another object of the present invention is to achieve the above object with an hermetically sealed switch in which there is an actuator that has actuating portions which are substantially rigid to maintain their dimensional characteristics but yet also have portions which are capable of easily flexing to effect transmission of the movement.

A further object of the present invention is to provide an hermetically sealed switch which achieves the above objects and which is relatively economical to manufacture and durable in use.

In carrying out the present invention, there is provided an hermetically sealed switch similar to the electric switch disclosed in my above-noted patent. This switch includes a snap action blade which is mechanically movable from its normal engagement with one contact to translate the movement into an electrical signal. The switch is mounted within a closed container that includes a corrugated tube which has a radial portion in alignment with the switch blade such that radial distortion of this portion toward the switch blade transmits the actuating movement to effect the snap action.

In the present invention at this portion of the tube there is positioned a stud which has a head which is engageable with a ball that in turn engages the blade such that movement of the stud is directly transmitted to the blade. The shank of the stud extends through the wall of the tube into its interior where it is engaged by an arm that is mounted on the container. The arm extends beyond one end of the tube to be engaged by an actuating link that is also secured on the exterior of the container.

Both the arm and the link are constructed and arranged so that they are normally rigid in a direction for transmitting motion to the shank but yet have flexible portions which permit the motion to be transmitted without detriment to the parts. Accordingly, through the use of the herein disclosed actuator, the mechanical characteristics of the switch are substantially maintained even with extended overtravel movement. Moreover the arm and link are normally biased in opposition to the actuating force, thus freeing the switch blade to return to its normally open position when the displacement is removed from the actuator.

Other features and advantages will hereinafter appear.

Referring to the drawing:

FIG. 1 is a side view of the hermetically sealed electrical switch of the present invention with portions being shown in section.

FIG. 2 is a section taken on the line 2-2 of FIG. 1.

FIG. 3 is a partial section similar to FIG. 1 of a modification showing a different support for the arm.

Referring to the drawing, the snap action electrical switch of the present invention is generally indicated by the reference numeral 10 and includes a body 11 on which are mounted three posts 12, 13 and 14. The post 12 supports one end of a contact blade 15 with its free other end carrying a contact 16, that normally engages a normally closed contact 17 carried by the post 13 and is movable to engage a normally open contact 18 carried by the post 14. The contacts 17 and 18 are respectively connected to lead terminals 19 and 20 while a terminal 21 is connected to the contact blade 15.

A rectilinear container 22 formed from sheet metal is positioned over the body 11 and is secured thereto by the use of a metal insert 23 which has an interior shape mating with the exterior periphery of a ledge 11a formed on the body. The insert 23 and the ledge 11a are secured along their adjoining surfaces by a hardened metal joint while a welded joint 24 secures the adjacent edges of the insert 23 and the container 22. With such a construction and as more specifically described in my above-noted patent, the bottom portion of the container 22 is hermetically sealed but yet electrical connections may be made to the contacts by use of the terminals 19, 20 and 21 that extend from the container.

In the upper portion of the container 22, forming an integral part thereof is a corrugated tube 25 which extends between the sidewalls of the container and is secured to each sidewall as by welded joints 26. In the embodiment shown in FIGS. 1 and 2, both ends of the tube are open as the end walls of the container have circular apertures into which the ends of the tube fit.

The normal position of the contact blade 15 is shown in solid lines wherein its contact 16 engages the normally closed contact 17 to electrically connect lead 21 to lead 19. A downward force or movement on the blade 15 will cause it to snap and move its free end from engagement with contact 16 to engagement with contact 18 to connect lead 21 to lead 20 as indicated by the dotted line position of the blade. Upon removal of the force on the blade, the natural resilience of the blade will cause it to resume its normal position.

In accordance with the present invention, the actuating force to the blade is effected by a flat head 27 of a stud 28 with the head 27 engaging a ball 29 which in turn engages the blade. A shank 30 of the stud 28 extends into the interior of the tube while welding 31 serves to form a seal between the stud and the tube. As shown, the tube is preferably formed with a flat cylindrical portion 32 for accommodating the stud and for preventing flexing of the tube where the stud is located.

The end of the shank 30 is engaged by an arm 33 which has a curved end 34 that extends through one end of the tube and is secured as by welding 35 to the adjacent sidewall of the container 22. The other end of the arm 33 extends beyond the other end of the tube and is engaged by a link 36.

The link 36 is essentially U-shaped and has one leg thereof secured as by welding 37 to the sidewall of the container while its other end is formed with a notch 38 into which the end of the arm 33 is fitted.

It will be appreciated that the arm 33 is channel shaped in cross section except for the arcuate end 34 to be substantially rigid between its engagement with the link 36 and the stud 28 but yet the curved portion 34 permits it to flex easily. The link 36 is a flat strip of metal bent into a U-shape to have a round corner 39 which provides for flexing while the other leg 40 has its junction with the bight portion made relatively rigid by reason of it being sharply bent. Actuating force is thus transmitted to the arm 33 through the length of the leg 40 which is rigid in the direction in which the force is transmitted but yet is capable of easy flexing by the corner 39.

If desired, the bight portion of the link 36 may be formed with an embossed upstanding dot 41 where the actuating force may be applied and additionally the bight portion may be formed with stamped ridges to provide additional rigidity if needed.

With the above construction, a downward actuating force exerted on the dot 41 causes a downward movement of the leg 40 and according pivotal movement of the arm 33 to effect radial distortion of the tube to enable inward movement of the stud 28 and a consequent actuation of the blade 15. Upon removal of the force the arm and link will return to their solid line position which permits the tube 25 to also return to its nondistorted position removing all force on the blade 15 so that it may return to its normal solid line position.

It will be understood that the movement of the link 36 effects flexing at the corner 39 while movement of the arm 33 is accommodated by flexing in the curved end 34. If an overtravel movement is applied to the link 36, the arm 33 will move downwardly until it abuts the end of the tube adjacent the notch 38 and subsequent actuating movement will be absorbed in the bight portion of the link 36. Thus substantial overtravel motion is accommodated by the actuator without permanently distorting either the arm or link or being applied to the contact blade.

Shown in FIG. 3 is a modification of the present invention in which there is provided a plug 42 for closing the opening in the sidewall of the container. The plug supports the curved end 34 of the arm 33 as for example by welding at 43. Thus in this embodiment only one end tube is open. If desired, the sidewall of the container could be utilized in place of the plug. It will be understood that while a specific type of switch has been disclosed, other types of switches requiring physical displacement for actuation may be employed if desired.

It will accordingly be appreciated that there has been disclosed an hermetically sealed electrical switch which has an actuator for transmitting an actuating motion to the switch through a radially distortable tube. The actuator includes an arm having a flexible end portion secured to the container and a free end portion which is engaged by a leg of a U-shaped link with the other end of the link being secured to the container. As the portions of the actuator which transmit motion to the switch are essentially rigid in the direction of motion and as they have flexible portions for accommodating the movement, the actuator resists physical deformation and accordingly maintains its mechanical operating characteristics over a wide range of movement.

Variations and modifications may be made within the scope

of the invention and portions of the improvements may be used without others.

I claim:

1. In an hermetically sealed electrical switch having a member mechanically movable from one position to another to provide an electrical signal and an hermetically sealed container enclosing said switch and including a radially distortable tube for transmitting mechanical movement through the container to the movable member, the improvement comprising an actuator having an arm and a link, said arm having a flexible end portion secured to the container and a rigid portion extending within the tube to engage the tube, said link having a flexible end portion secured on the container and a rigid portion with the rigid portion of the arm engaged by the rigid portion of the link and in which an actuating movement applied to the link is transmitted by the rigid portions to the tube to effect distortion thereof to cause actuation of the switch.
2. The invention as defined in claim 1 in which the link is formed to have a somewhat U-shape, and in which the flexible end portion includes one leg and a curved junction with the bight portion.
3. The invention as defined in claim 2 in which the rigid portion of the link includes the other leg with a relatively rigid junction between the other leg and the bight portion and in which the actuating movement is applied to the bight portion.
4. The invention as defined in claim 1 in which the rigid portion of the arm is straight and substantially channel shape in section, and in which said rigid portion extends out of one end of the tube to be engaged by the rigid portion of the link and to have the tube limit movement of the arm.
5. The invention as defined in claim 4 in which the flexible portion of the arm is curved and extends out the other end of the tube to be secured to the sidewall of the container exteriorly of the tube.
6. The invention as defined in claim 4 in which the flexible portion of the arm is curved and is secured within the tube to the container.
7. The invention as defined in claim 1 in which the tube is annularly corrugated substantially throughout its length but has a cylindrical portion aligned with the movable member, a stud secured in the cylindrical portion having a head positioned within the container for transmitting motion to the movable member and a shank extending into the tube and in which the rigid portion of the arm engages the end of the shank.
